(57) CLAIM

The ornamental design for a cover for water closet tank, as shown and described.

DESCRIPTION

In a preferred embodiment, the nature of this product is as a plumbing fixture which is primarily useful for covering the tank of a water closet.

FIG. 1 is a right, top, front perspective view of a cover for water closet tank embodying my new design;

FIG. 2 is a top plan view thereof;

FIG. 3 is a right side elevational view thereof, the left side elevational view being a mirror image of the right side shown; and,

FIG. 4 is a front elevational view thereof.
